(57) **CLAIM**

The ornamental design for an adapter for a liquid dispensing syringe, as shown and described.

DESCRIPTION

FIG. 1 is a perspective view of an adapter for the liquid dispensing syringe.

FIG. 2 is a front view of the adapter with the rear view being a mirror image thereof.

FIG. 3 is a right side view of the adapter with the left side view being a mirror image thereof.

FIG. 4 is a top view of the adapter; and,

FIG. 5 is a bottom view of the adapter.

The broken lines in the figures are shown for the purpose of illustrating boundaries of the claimed design and the areas inside the broken line boundaries form no part of the claimed design.

1 Claim, 2 Drawing Sheets
